UNITED STATES PATENT OFFICE

93,568

DESIGN FOR A BURIAL VAULT OR ARTICLE OF SIMILAR NATURE

Claude R. Neff, Camden, Ohio, assignor to The
Neff & Fry Company, Camden, Ohio, a corpora-
tion of Ohio

Application July 11, 1934, Serial No. 52,543

Term of patent 7 years

To all whom it may concern:

Be it known that I, CLAUDE R. NEFF, a citizen
of the United States of America, residing at
Camden, in the county of Preble and State of
Ohio, have invented a new, original, and ornamental
Design for a Burial Vault or Article of
Similar Nature, of which the following is the spec-
ification, reference being had to the accompany-
ing drawing, forming a part hereof;

Figure 1 is a perspective view of a burial vault,
showing my new design.

Figure 2 is an enlarged plan view of one of the
corners of the burial vault, showing a detail of
my design.

Figure 3 is an enlarged detail in perspective of
a portion of one of the corners of my vault.

I claim:

The ornamental design for a burial vault or
article of similar nature, as shown.

CLAUDE R. NEFF.
